STRAIGHTENING MACHINE

William J. Tedhunter, Newcastle, New South Wales, Australia

Application August 2, 1939, Serial No. 287,916

10 Claims. (Cl. 153—48)

The invention relates to means for straightening structural sections, such as bars, beams, channels, rails and the like. Where, in the following description, these structures are referred to as "bars," it is meant to include any of the several kinds of stock enumerated.

The object is to provide convenient and efficient means for operating upon the bar whereby the straightening force may be applied at required points on either side, without withdrawing it from the machine until the entire straightening has been completed.

The invention comprises movable heads provided with oppositely acting gags; each head being provided with a lifting gag and flanking, stationary gags which are horizontally adjustable toward and away from their respective lifting gags.

Means are provided for lifting either lifting gag while the other lifting gag remains in operative position, whereby either or both sides of the bar may be gagged as required, without removing it from the machine in order to turn it over.

The engaging faces of the lifting gags are positioned so as to project beyond or in advance of the engaging faces of the two stationary gags which flank the lifting gags, so that only the stationary gags of one head, cooperate with the lifting gag of the other head.

The invention also comprises improved means for supporting and presenting the bars, especially T-rails to the operation of the gags.

Means are also provided whereby, when one lifting gag is lifted, it moves away from the operative position, to a position sloping away from the vertical plane of the bar, in order to afford a better view of the operation of the machine.

The invention also comprises improvements in details of construction and operation.

Referring to the drawings which illustrate merely by way of example a suitable embodiment of the invention:

Fig. 1 is a plan view of the machine in accordance with my invention.

Fig. 2 is a side elevation partly in section, of the same.

Figs. 3 and 4 are fragmentary elevations, on an enlarged scale, showing the table rolls in different positions, especially adapted for operation upon T-rails.

Similar numerals refer to similar parts throughout the several views.

In accordance with the example herein illustrated, the machine comprises two movable heads 7 and 8, mounted on the frame or bed 9.

The head 7 is operated by means of cams, or eccentrics 12 and 12', driven by motor 13, through suitable gearing, as shown.

The reciprocating movement of head 7 on the bed 9, is limited to the actuation derived from the cams or eccentrics 12 and 12'.

The head 8 is also movably mounted upon the bed 9 and is adapted to be moved into desired position of adjustment by the screws 10 and 10', which are actuated by the motor 11, through 10 suitable gearing as shown.

Between the head 8 and the screws 10 and 10', are inserted the cast-iron breaker blocks 14, the purpose of which is to break, in case the head 8 is put under too great a strain, that is to say, the 15 breaker block is the weakest link.

The head 7 is provided with the lifting gag 15, which is operated by the air cylinder 16.

When lifted, this gag 15 is moved away from the perpendicular. That is to say, by means of the 20 groove 22, in the head 7 in which the gag 15 travels and which is inclined to the perpendicular, the gag, as it moves upwardly, also moves away from the perpendicular plane of the bar being operated upon. The object of which is to allow 25 the operator a better view of the straightening operation.

The head 7 is also provided with two gags 17 and 17' which flank the gag 15 and are horizontally adjustable toward and away from the 30 lifting gag 15.

These two gags 17 and 17' are operated simultaneously into desired position of adjustment by means of a right and left hand screw 18, which is actuated by the motor 19 through a worm and 35 sprocket and chain gearing.

The head 8 is provided with the lifting gag 20 which is adapted to be lifted by means of an air cylinder 16'. The method and means for operating this gag 20 is similar to that above described with respect to gag 15.

Head 8 is also provided with the two gags 21 and 21' which are horizontally adjustable, and are operated in the same way and by mechanism similar to that shown for operating the gags 45 17 and 17'.

The rolls 24, shown in Fig. 1, indicate the positions of the end table rolls on each side of the machine. These rolls, in the present invention, 50 are not motor driven, and serve in connection with positioning and supporting the bar during the straightening operation.

For properly operating upon certain kinds of stock, for example T-rails, a series of table rollers 55

are provided. These rolls are mounted in movable bearings, as shown in Figs. 3 and 4.

In Fig. 3, the rail 25 is shown in the upright position resting squarely upon its horizontal supporting flange 25', which rests upon the horizontal rollers 23. In this position the straightening operation is effected in the usual way by the cooperating action of the lifting gag 20 and the stationary gags 17 and 17' upon the flange portion 25'.

As shown in Figs. 3 and 4, each roller 23 is supported on the bearings 26 and 27. The bearing 26 is supported to move vertically up and down, and is so actuated by the air cylinder 28. Guide 15 29 is provided with each bearing 26, to keep the several rolls or rollers in proper alinement.

The bearing 27, at the other end of the roll, is pivotally supported at 30 in order to permit the tilting or canting of the roller from a horizontal position, as shown in Fig. 3, to a position inclined to the horizontal, as shown in Fig. 4.

The purpose of this inclined position of the supporting roller, as shown in Fig. 4, is as follows:

Where for example, the straightening forces are to be applied to the opposite margins of the flange 25', the rollers should all be horizontal, as shown in Fig. 3, but where the straightening force is applied to the top and bottom of the rail, these contacting surfaces or points must be in a line at right angles to the contacting surfaces of the gags. In other words the line of pressure, or straightening force, must be through the middle of the web 31 and at right angles to the plane 35 of the flange 25'. Otherwise there would be a distortion of the web, rather than a straightening of the rail.

Each roller 23 is preferably driven by an individual motor, as at 36 and each bearing 26 is individually operated by its respective cylinder 28.

While the means herein shown and described, for securing the proper support and presentation of the rail to the gags, are considered the most satisfactory, as providing extremely simple means for a substantial range of adjustment. Other means may be used for directing the line of force through the web and at right angles to the planes of the contacting faces of the gags, by securing the desired inclinations of the rail supporting surfaces, and still be within the scope of the claims. For example suitably tapered rollers may be used.

The arrangements of the parts last above described is the opposite to that shown in Fig. 2. That is to say, the positions of gags 15 and 20 are reversed.

The shims 32 beneath the bearing 26 are for detail adjustment of the bearing upon its supporting frame or formation 33, which is pivotally connected at 34 to the piston rod 35 of air cylinder 28.

In operation.—The head 8, for example, is placed in such a position as to allow the bar, which is to be straightened, to lie between the lifting gag 15 on head 7, and the two gags 21 and 21' on head 8. Also these gags 21 and 21' are placed at the centers required for the bar to be straightened.

These flanking gags, being operated simultaneously by a right and left hand screw, are always equi-distant from their respective lifting gags.

If the blow for straightening the bar is to be delivered by gag 15, then gag 20 is lifted up out

of the way, so that the other side of the bar will rest against gags 21 and 21' whilst the blow is being delivered.

When the motor 13 is started, the head 7 moves backward and forward on the bed 9, the amount of travel delivered by the cams or eccentrics 12 and 12'.

At the same time, the head 8 is pushed forwardly by means of the screws 19 and 19' into required position of adjustment, that is, until the requisite strength of the blow of gag 15 is given. This operation gags one side of the bar only.

To gag the other side, gag 15 is lifted and gag 20 is dropped.

As the lifting gags 15 and 20 are in advance of their respective horizontally adjustable flanking gags when either lifting gag 15 or 20, is used, the flanking gags on the same side of the machine are out of action.

It will thus be seen that, in accordance with the invention above described, convenient means are provided for gagging the bar or similar stock, on both sides thereof, without removing the bar from the machine, turning it over and placing it back in the machine, and also whereby the lifted gag may be so disposed as not to obstruct the view.

The present invention is especially adapted for operation upon T-rails, and is to be contrasted with the now common practice which has prevailed for at least half a century without substantial improvement. In accordance with said common practice the straightening of T-rails is a laborious job, requiring the employment of a large number of men.

In accordance with the invention herein described and claimed, all of such laborious work is eliminated, as the entire job of manipulating and straightening is accomplished by mechanical means.

What I claim is:

1. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position.

2. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, said heads also carrying laterally adjustable cooperating gags.

3. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, each lifting gag being provided with a counterbalance

- tending normally to hold it in inoperative position.
4. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, each lifting gag being provided with a power controlled counterbalance adapted to hold the gag in inoperative position upon failure of said power. 10
5. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, flanking gags carried by each head, and power operated mechanism also carried by each head for controlling said gags carried thereby. 15
6. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, means for causing reciprocating movement of one head, and power operated means for adjusting, from time to time, the position of the other head during the straightening operation, in order to control progressively said operation. 20
7. In a straightening machine, the combination of a supporting frame, a pair of heads mounted thereon adapted to move toward and away from each other, each head provided with a guide-way extending upwards from the frame, said guide-ways being oppositely positioned and diverging upwardly one from the other, a lifting gag movable in each guide-way upward from operative to inoperative position and downward from inoperative to operative position, a pair of flanking gags supported upon and moving with each head and transversely adjustable thereon, controlling means mounted on each head, comprising motor and gear mechanism for the flanking gags and a power cylinder for the lifting gags. 25
8. In a straightening machine, the combination of a supporting bed, two heads mounted thereon and relatively movable toward and away from each other, each head provided with a lifting gag, and horizontally adjustable flanking gags, a plurality of table rollers flanking the machine, each roller having one end-bearing vertically adjustable, and the other end-bearing pivotally supported, and means for arbitrary vertical adjustment of said vertically adjustable bearing adapted to secure the required axial inclination of the roller for cooperation with rails varying in cross-sectional contour. 30
9. In a straightening machine, the combination of a supporting bed, two heads mounted thereon and relatively movable toward and away from each other, each head provided with a lifting gag and horizontally adjustable flanking gags, a plurality of table rollers flanking the machine, each roller having one end-bearing vertically adjustable, and the other end-bearing pivotally supported, each of said rollers provided with an independently controlled motor drive, and adapted for cooperation with rails varying in cross-sectional contour. 35
10. In a straightening machine, the combination of a supporting bed, two heads mounted thereon and relatively movable toward and away from each other, each head provided with a lifting gag and horizontally adjustable flanking gags, a plurality of table rollers flanking the machine, each roller having one end-bearing vertically movable, and the other end-bearing pivotally supported, and adapted for cooperation with rails varying in cross-sectional contour, each vertically movable bearing being independently adjustable. 40

WILLIAM J. TODHUNTER.
